[57] **CLAIM**

The ornamental design for a sliding truck bed, as shown and described.

DESCRIPTION

FIG. 1 is an exploded perspective view of the front, top and one side of a sliding truck bed showing our new design;

FIG. 2 is a front elevational view thereof;

FIG. 3 is a rear elevational view thereof;

FIG. 4 is a side elevational view thereof, the side opposite being a mirror image of the side shown in FIG. 4;

FIG. 5 is a top plan view thereof;

FIG. 6 is a bottom plan view thereof; and,

FIG. 7 is a bottom perspective view thereof.

FIG. 2.

FIG. 3.

FIG. 6.

FIG. 7.
